UNITED STATES PATENT OFFICE.

LEDWIG WILHELM SEESER, OF RAGUHN, GERMANY.

FIGURED COVERING.

No. 812,531.

Specification of Letters Patent.

Patented Feb. 13, 1906.

Application filed September 18, 1905. Serial No. 279 058.

To all whom it may concern:

Be it known that I, LEDWIG WILHELM SEESER, a subject of the King of Bavaria, and a resident of Raguhn, Duchy of Anhalt, Germany, have invented certain new and useful Improvements in Figured Coverings, of which the following is a specification.

The object of this invention is to produce by a combination of figured or diapered tissue with another material a novel figured covering for floors, walls, ceilings, or the like, the essential feature of which combination is that the figured tissue is united with the other stuff in a manner that their figured or ornamented sides form the outsides and the covering is used with the figured tissue forming the top surface. By this invention there is attained that a figured or diapered covering can be produced in a more simple and less expensive way than hitherto.

Until now figured tissues were produced either by pointing or printing the pattern upon the covering when it was ready. There are also other more or less troublesome and expensive processes known for producing coverings figured through and through. For producing this new figured covering either a tissue of threads of various colors is used or a tissue on which the pattern is printed. In both cases the figured tissue can be produced at a proportionately small cost and much cheaper than the figuring of already-finished coverings, as the figured tissue can either at once be woven out of colored threads on the loom or also tissue of one color can be printed on after the manner of cloth-printing, which is much cheaper than printing or painting on the ready-made covers. The thus-prepared figured tissue is then united on its back with the other stuff by pressing or other means, or eventually it is embedded in the same, for which there are some very simple continuous processes, so that also this part of the manufacturing process is not expensive. The figured covering is then completely ready and does not require any further process, so that in consequence of this it becomes a considerably cheaper article.

As a base or bottom material linoleum, paper, or any other suitable mass—for instance, wood-pulp, cellulose, or the like—may be used, or two or several layers of the tissue may be used and the same be united by paste, putty, cement, or the like, or between the different layers an intermediate layer of a sticky, felty, or other material—for instance,

paper—may be placed adapted to fill any open spaces or meshes of the tissue, so that no dust or dirt can penetrate into the covering. In order to firmly unite the tissue with the bottom material, the tissue may be irregularly cross-weaved—as, for instance, tweed or the like or also of threads of different thicknesses. Thereby is attained an unevenness of the contact-surface of the tissue with the bottom material adapted to bring about a good and reliable union of the two.

If the bottom material on pressing the covering passes through the meshes of the tissue, it may, by its own color aid in the figuring of the tissue, so that if, for instance, a tissue of only two colors is used a three-colored figuring of the covering will (if the bottom material is one-colored) be produced if the same penetrates through the meshes of the tissue. If more than one layer of tissue is used for forming the covering, the patterns of the different layers may either exactly cover each other, so that the covering will show on both sides the same pattern, or the single layers of the tissue may show various patterns, and these different patterns when they are visible through the open meshes of the other layers of tissue or enter into the same may work together to form one whole as a pattern. A covering consisting only of layers of tissue may then be used as desired on both sides, as it will show either on both sides the same or different patterns. Under the main layer of the figured tissue pieces of tissue of various colors cut to form different figures or patterns may be placed and united with the same by pressing, so that a further figuring of the covering will take place according to the shapes of the said pieces.

By means of this invention carpets, rugs, and the like, and in general coverings for floors, walls, ceilings, and so on can be produced which are similar to textile fabrics, so that figured tissues or fabrics will find an increased use. It is evident that in the production of such coverings also light and inferior materials may be used, which for themselves alone could not be used for coverings. The tissue may before or after being united with the other material be suitably impregnated. If the figured tissue is produced by printing, the printing is preferably done with oil colors in a manner that the color soaks through the whole thread, so that the thread, though it had originally a color different from that of the pattern, will retain the color

quite as long as if it had been given to it originally and until the last fiber is used up.

It would of course be no deviation from the principle of this invention if first a tissue 5 of one color only were united with the base or bottom material and thereupon the tissue figured by printing or other means, as the product would in both cases be the same; but the latter mode of manufacture would be far 10 less advantageous than the above described.

What I claim as my invention, and desire to secure by United States Letters Patent, is—

1. A composite covering for floors, walls, 15 ceilings and the like consisting of a colored or figured base layer, and a colored or figured covering-tissue of fabric or textile material

so united with the base layer that the coloring or figuring of the latter combines with that of the covering to form the complete 20 figured or colored effect.

2. A composite covering for floors, walls, ceilings, and the like, consisting of a colored or figured base layer, and an open-mesh textile colored or figured covering tissue or fabric 25 united to the base layer and arranged to expose therethrough the coloring or figuring of the base layer.

In witness whereof I have hereunto set my hand in presence of two witnesses.

LUDWIG WILHELM SEESER.

Witnesses:

HENRY HASPER,
WOLDEMAR HAUPT
